BRACKET FOR BEDS OR LIKE ARTICLES

James L. Morrison, Brecksville, Ohio, assignor to The Master Products Company, Cleveland, Ohio, a corporation of Ohio

Filed Jan. 12, 1962, Ser. No. 68,284

Term of patent 14 years

(Cl. D5—2)

FIG. 1 is a front elevational view of the bracket for beds or like articles embodying the design;

FIG. 2 is an end view of the bracket for beds or like articles taken from the right hand side of FIG. 1;

FIG. 3 is an end view of the bracket for beds or like articles taken from the left hand side of FIG. 1;

FIG. 4 is an elevation taken from the back of the bracket for beds or like articles;

FIG. 5 is a top plan view of the bracket for beds or like articles;

FIG. 6 is a bottom plan view of the bracket for beds or like articles; and

FIG. 7 is a perspective view of the bracket embodying the design.

I claim:

The ornamental design for a bracket for beds or like articles, substantially as shown.
